UNITED STATES PATENT OFFICE

HARRY DIXSON, OF PELLA, IOWA, ASSIGNOR TO ROLSCREEN COMPANY, OF DES MOINES, IOWA

GUIDE AND MOUNTING FOR SCREENS OR THE LIKE

Original application filed August 16, 1926, Serial No. 129,566. Divided and this application filed December 29, 1927. Serial No. 243,327.

The object of my invention is to provide a guide and mounting for screens or the like wherein the guide may be adjusted toward or from its mounting and so that adjustment 5 of the guide relative to the mounting may be easy and quickly obtained.

More particularly my invention relates to a guide mounting wherein a channel shaped groove member forming a mounting for receiving a guide element is adapted to be embedded in the plastic material adjacent a window opening whereby the guide is frictionally held in position so that within the groove of the mounting the guide may move 15 towards or from the back of the mounting.

Still a further object is to provide a mounting formed of a strip of metal adapted to form a base or back element with a pair of angular members secured thereto with one 20 flange of each of the angular members spaced from the other corresponding flange of the other member wherein a slit opening is formed between the two angular members into which a guide is adapted to be mounted 25 and to be frictionally held by parts of the two angular members.

My present application is a division of my copending application Serial Number 129,566, filed August 16, 1926 which will 30 mature into Letters Patent No. 1,655,260 on January 3, 1928.

With these and other objects in view, my invention consists in the construction, arrangement and combination of the various 35 parts of my guide and mounting for screens or the like, whereby the objects contemplated are attained, as hereinafter more fully set forth, pointed out in my claims, and illustrated in the accompanying drawings, in in 40 which:

Figure 1 is a front elevation of a portion of a building having a window opening equipped with a window screen structure and my improved guide mounting and guide, 45 parts being broken away and shown in section to better illustrate the construction.

Figure 2 is a horizontal sectional view taken on the line 2—2 of Figure 1.

Figure 3 is a detail sectional perspective 50 view of a portion of my guide mounting.

Figure 4 is a detail sectional view illustrating the guide mounting embedded in plastic material and showing the relationship of the guide and screen to the mounting; and

Figure 5 is an end view of the guide mounting illustrating the angular members and two flanges thereof converging toward each other for forming a restricted throat. 55

In the accompanying drawings, I have used the reference numeral 10 to indicate 60 generally a wall covered with plastic material and 21 to indicate a window opening. Within the window opening 12 is installed a steel window structure 14 which includes a metal frame and the sash hinged thereto. 65

This style of window is sometimes called "casement windows."

In the upper part of the window opening there is provided in the wall, a suitable recess 16 to receive a rolling window screen casting or box 18. The box 18 contains a roller (not shown) onto which the screen 20 may be wound or unwound. 70

In connection with the screen 20 it is necessary to provide suitable guides at each side thereof which guides are necessarily mounted within the plastic material on each side of the window opening. The screen 20 has at its lower end, a binder strip 22 which is provided with a friction block or end piece 80 24 adapted to extend into a guide 26. 75

In order to mount the guides 26 and to properly hold them in position, I provide a guide mounting A. The guide mounting A includes a flat strip or back element 28 to 85 which is riveted or spot welded a pair of angular members 30.

One flange of each of the angular members 30 is adapted to rest against the back piece or element 28 and each of the other flanges of the members 30 project away from the back 28 substantially at right angles thereto. 90

It thus follows that two of the flanges of the angular members 30 are opposed to each other and as shown in Figure 5 of the drawings, are slightly spaced from each other so as to provide a slit opening 32. The slit opening 32 is designed to receive a portion of the guide 26. The two flanges of the members 30 which form the slit opening 32 100

converge toward each other so that a restricted neck 34 is formed adjacent the mouth of the slit opening 32.

The extreme outer ends of the flanges which form the slit opening 32 are bent outwardly or away from each other as at 36. The entire guide mounting as shown in Figure 3 of the drawings, is adapted to be embedded in the plastic material as shown in Figure 4 of the drawings.

In the form of guide as shown in the drawings, I provide a fastening flange 38 which projects into the slit opening 32. The fastening flange 38 is forced through the restricted neck 34 thus insuring frictional engagement of the angular members with the fastening flange 38. The guide 28 is thus supported and mounted by means of the guide mounting A and is capable of adjustment towards or from the back 28 due to the frictional engagement of the angular members with the guide element or flange 38 thereof.

It is quite desirable to have the guides removable from their holders so that when the wall 10 is painted, the guides may be removed if desired and in the event of the guides becoming injured or broken for any cause, new ones can be inserted in the holders A. The holders A are practically invisible when the screen guides are removed and do not mar the interior of the house or its finish.

In the event that the window opening varies in distance between the two walls in which the holders A are mounted, then the guides 26 may adjust themselves towards or from the holder proper depending upon the length of the binder element 22 which practically adjusts the position of the guide elements 26.

It will be noted that the friction blocks 24 mounted upon the binder 22 travel within the guides 26 and that the binder 22 serves as a spacing element for properly positioning the guide elements relative to each other. It will thus be seen that any slight variation in the distance between the holders A may be compensated for by inward or outward movement of the guides which are frictionally retained by the holders A.

Some changes may be made in the details of the construction and arrangement of the parts of my improved guide and mounting for screens or the like, without departing from the purposes and scope of my invention, and it is my intention to cover by my claims, any such changes as may be reasonably included within their scope.

I claim as my invention:—

1. A guide and mounting including a back element having a pair of opposed spaced angular members secured thereto for forming a guide holder with a slit opening between said angular members, a screen guide having a fastening flange thereon, said fastening

flange adapted to extend into said slit opening and be received between parts of said angular members, said parts of the angular members frictionally engaging the fastening flange for holding it in position and permitting the guide to be adjusted towards or from the holder as and for the purposes stated. 70

2. A guide and mounting including a guide holder having a slit opening therein, a screen guide adapted to extend into said slit opening and be received between parts of said holder, parts of said holder frictionally engaging the screen guide for holding it in position. 75

3. A guide and mounting including a guide holder having a slit opening therein, a screen guide adapted to extend into said slit opening and be received between parts of said holder, said parts being inclined towards each other whereby a restricted neck is formed adjacent the mouth of said slit opening, said last parts frictionally engaging the screen guide for holding it in association with the holder and allowing it to be adjusted laterally within the slit opening and 90 between said parts. 80

4. A guide and mounting including a back element having a pair of opposed spaced angular members secured thereto for forming a guide holder with a slit opening between said angular members, a screen guide adapted to extend into said slit opening and be received between parts of said angular members, said parts of the angular members engaging the guide and holding it therebetween and permitting the guide to be adjusted towards or from the back element as 95 and for the purposes stated. 100

5. A track mounting including a member having a slit opening therein, a track having a fastening flange thereon, said fastening flange adapted to extend into said slit opening and be received between parts of said member, parts of said member frictionally engaging the fastening flange for holding it in position and permitting the track to be adjusted towards or from the member as and for the purposes stated. 105

6. A track mounting including a member having a slit opening therein, a track having a fastening flange thereon, said fastening flange adapted to extend into said slit opening and be received between parts of said member, parts of said member frictionally engaging the fastening flange for holding it 110 in position. 115

7. A track mounting including the forming of slit opening, a track, a fastening flange of substantial width on said track, said flange adapted to fit snugly into said slit opening and have its surfaces frictionally engage the material on the sides of the slit opening whereby the track may be mounted and held in position in said slit opening. 125

8. A track mounting including a member 130

- having a slit opening, a track, a fastening flange of substantial width on said track, said flange adapted to fit snugly into said slit opening and have its surfaces frictionally engage the material on the sides of the slit opening whereby the track may be mounted and held in position in said slit opening.
9. A track mounting including the forming of slit opening, a track, a fastening flange of substantial width on said track, said flange adapted to fit snugly into said slit opening and have its surfaces frictionally engage the material on the sides of the slit opening whereby the track may be mounted and held in position in said slit opening the substantial width of said fastening flange permitting the track to be adjusted towards or from the mouth of the slit opening.
10. A track mounting including a clip adapted to be embedded in plastic material, said clip having a pair of sides inclined towards each other for forming a restricted passage therebetween, the free edges of said sides being inclined away from each other and a track having a flat fastening flange thereon adapted to be received between said sides and extended through the restricted passages and frictionally engaged thereby for holding the track in position.
11. A track mounting including a clip adapted to be embedded in plastic material, said clip having a pair of sides inclined towards each other for forming a restricted passage therebetween and a track having a flat fastening flange thereon adapted to be received between said sides and extended through the restricted passage and frictionally engaged thereby for holding the track in position.
12. A track mounting including a channel member adapted to be embedded in a plastic wall and a guide track supportingly associated within said channel member.
13. A track mounting including a channel member adapted to be embedded in a plastic wall and a guide member adjustably supported by said channel member and at least a part of said guide member projecting within said channel member.
14. A track mounting including a channel member mounted on a wall with its open side facing away from the wall and a guide member associated with said channel member and at least a portion of said guide member being received within the channel member.
15. A guide mounting for the side edge of a roll screen comprising a channel member permanently mounted with respect to a wall surface and a guide track removably supported relative to said channel member.
16. A guide mounting of the class described comprising a channel receiving member and a guide track associated therewith.
17. A guide mounting of the class described comprising a channel receiving mem-
- ber adapted to be mounted within a plastic wall and a guide track associated therewith.
18. A guide mounting of the class described comprising a channel receiving member and a guide track associated therewith and having at least a portion thereof received within said channel member.
19. A guide mounting for the side edge of a roll screen comprising a receiving member and a guide having at least a portion of itself received within said receiving member, said last portion being adjustable whereby the guide may project at different distances with respect to the mouth of said receiving member.
20. A guide mounting for the side edge of a roll screen comprising a receiving member adapted to be embedded in a plastic wall, said receiving member having two substantially similar walls.
21. A guide mounting for the side edge of a roll screen comprising a receiving member adapted to be embedded in a plastic wall and having its mouth opening away from the surface of the plastic material.
22. A guide mounting for the side edge of a roll screen comprising a receiving member of greater depth than width and adapted to be embedded in a plastic wall.
23. In a device of the class described, comprising a receiving member adapted to be embedded in the plaster of a wall, said receiving member having no greater depth than the thickness of said plaster.

Des Moines, Iowa, December 23, 1927.
